(57) **CLAIM**

The ornamental design for a specimen collection device, as shown and described.

DESCRIPTION

FIG. 1 shows a perspective view of the specimen collection device of the present invention.

FIG. 2 shows a side elevation view thereof.

FIG. 3 shows a top plan view thereof.

FIG. 4 shows a bottom plan view thereof.

FIG. 5 shows a rear elevation view thereof; and,

FIG. 6 shows a front elevation view thereof.

The broken lines shown in the FIG. 1 represent a specimen container adapted to be supported by the present invention, which is an environmental effect that forms no part of the claimed design.
